UNITED STATES PATENT OFFICE.

LOUIS W. SOUTHGATE, OF WORCESTER, MASSACHUSETTS, ASSIGNOR TO THE AUTO PNEUMATIC ACTION COMPANY, A CORPORATION OF NEW YORK.

TRACKING DEVICE.

1,163,274.

Specification of Letters Patent. Patented Dec. 7, 1915.

Application filed March 18, 1912, Serial No. 684,487. Renewed May 17, 1915. Serial No. 28,772.

To all whom it may concern:

Be it known that I, Louis W. Southgate, a citizen of the United States, residing at Worcester, in the county of Worcester and 5 State of Massachusetts, have invented a new and useful Tracking Device, of which the following is a specification.

The object of this invention is to provide a new and improved apparatus for causing 10 a perforated note-sheet to run correctly with relation to a tracker. The device has been primarily designed for use in connection with automatic musical instruments.

The invention is shown in the accompanying drawing forming part of this application for patent in which,

Figure 1 is a front elevation partly in section of the mechanism, and Fig. 2 is a plan view partly in diagram.

20 Referring to the drawing and in detail, A designates the spool box which has arranged therein, the usual journals 10 and 11 on which a music spool B carrying the perforated note-sheet C can be placed in the 25 usual manner. The left-hand journal 10 fits in a casing 12 which carries the usual spring 13 tending to press the journal 10 outwardly.

D designates the tracker arranged in the spool box, and E the usual take-up spool 30 which is actuated to draw the note-sheet forward over the tracker bar. Arranged in the back of the spool box are blocks 14—14. Spring arms 15—15 are secured to these blocks and project through holes 16—16 cut 35 in the tracker. These arms are made of flexible metal and are bent so that they will just clear the edges of the note-sheet when the same is in proper lateral position on the tracker. Contact arms 17—17 are also se- 40 cured to the blocks 14—14 to coöperate with the spring arms 15 to form electrical contacts to control the electro-magnetic mechanism hereinafter described. This electro- 45 magnetic mechanism consists of two electro- magnets F and F' connected to a source of electricity, as a battery X, by a wire or conductor 18. The battery also connects by wires or conductors 19 to the spring arms 15—15. The right-hand electro-magnet F

50 connects by a wire or conductor 20 to the left-hand contact arm 17 and the left-hand magnet F' connects by a wire 21 to the right-hand contact arm 17. These parts are so arranged that when the note-sheet is in normal

position on the tracker, it will not close 55 either contact, but so that if it wanders to the left, it will close the circuit through the wire 20 and magnet F, and so that if it wanders to the right, it will close the circuit through the wire 21 and magnet F'. 60

The magnets are arranged to control pivoted keepers or armatures G—G' which carry valves H—H' which cover control openings I—I' arranged appurtenant to the tracker, and which control openings regulate the operation of the pneumatic apparatus. This pneumatic apparatus consists of two pneumatics J and J' arranged on a base K and connected to operate together by an arm or link 23. Each pneumatic is controlled by a double valve 24 operated by a diaphragm 25. The control openings are connected by pipes 26 under said diaphragms. The diaphragms are arranged in a passage-way 27 which is connected to the 75 vacuum inducing apparatus of the instrument. The right-hand pneumatic J is connected by link 28, bell-crank 29, link 30, arm 31, shaft 32, arm 33, link 34, arm 35, shaft 36 and cam 37 to operate the left-hand 80 journal 11.

In operation, if the note-sheet for illustration, wanders to the left, the circuit through wire 20 and magnet F will be closed. This magnet will lift the valve H from the 85 control opening I, and will allow air to pass under the right-hand diaphragm, which will lift the right-hand valve 24 and allow air to flow into pneumatic J. When this operation takes place, the journal 11 will be allowed to move to the right and the spring 12 acting on the journal 10, will force the music spool slightly to the right to correct the left-hand wandering of the note-sheet. When the correction is made, the electrical contact 90 is broken and the apparatus ceases operation. If the note-sheet wanders too far to the right, the circuit is completed through the left-hand magnet F' and the left-hand pneumatic J' will move the journal 11 slightly to the 100 left and adjust the note-sheet automatically back to proper tracking position.

The spring arms 15—15 and the contact arms 17—17 are preferably made out of flexible metal so they can be bent and ad- 105 justed to get a very delicate operation of the apparatus.

Having thus fully described my invention,

what I claim and desire to secure by Letters-Patent is:—

1. In an automatic tracking device for a perforated note-sheet, the combination of the tracker, a spring arm projecting through the tracker, a contact for the spring arm, electro-magnetic means connected to said contact and spring arm, and pneumatic means for adjusting the lateral relation between the note-sheet and tracker controlled by the electro-magnetic means.

2. In an automatic tracking device for a perforated note-sheet, the combination of the tracker, two spring arms extending through the tracker and arranged to project so that the perforated note-sheet can run between the same, contacts coöperating with said spring arms, electro-magnetic means controlled by said contacts, and a pneumatic apparatus controlled by said electro-magnetic means for adjusting the relation of the note-sheet and tracker.

3. In an automatic tracking device for a perforated note-sheet, the combination of the spool box, a tracker mounted therein, spring arms arranged in the spool box behind the tracker and having their ends projecting through the tracker so that the perforated

note-sheet can run between the same, contacts arranged in said spool box to coöperate with 30 said spring arms, electro-magnetic means controlled by said contacts and spring arms, and pneumatic adjusting mechanism for adjusting the lateral relation between the note-sheet and controlled by said electro-magnetic 35 means.

4. In an automatic tracking device for a perforated note-sheet, the combination of the spool box, a tracker mounted therein, spring arms arranged in the spool box behind the 40 tracker and having their edges projecting through the tracker so that the perforated note-sheet can run between the same, contacts arranged in said spool box to coöperate with 45 said spring arms, electro-magnets controlled 45 by said contacts and said spring arms, primary valves controlled by said magnets, secondary valves, and pneumatics connected to adjust the music spool.

In testimony whereof I have hereunto set 50 my hand, in the presence of two subscribing witnesses.

LOUIS W. SOUTHGATE.
